UNITED STATES PATENT OFFICE.

JOHN F. STRATTON, OF BROOKLYN, NEW YORK.

CORNET.

SPECIFICATION forming part of Letters Patent No. 426,398, dated April 22, 1890.

Application filed September 28, 1889. Serial No. 325,375. (No model.)

To all whom it may concern:

Be it known that I, JOHN F. STRATTON, of Brooklyn, in the county of Kings and State of New York, have invented a new and Improved 5 Cornet, of which the following is a full, clear, and exact description.

The invention relates to the French or Pyrenet piston-valve cornet; and its object is to provide a new and improved cornet, which 10 when played upon produces a rich, full, and sweet tone.

The invention consists in certain parts and details and combinations of the same, as will be described hereinafter, and then pointed out 15 in the claim.

Reference is to be had to the accompanying drawings, forming a part of this specification, in which similar letters of reference indicate corresponding parts in both the figures.

20 Figure 1 is a side elevation of the improvement, and Fig. 2 is a sectional plan view of the same on the line $\alpha\alpha$ of Fig. 1.

The improved cornet A is provided with the usual mouth-piece B, inserted in the pipe C, leading into the first valve D, alongside of 25 which are arranged the second and third valves E and F, respectively. The valves D and E are connected with each other by the short pipe G, and in a similar manner the 30 valve E is connected with the valve F by a short pipe H. From the third valve F leads the end pipe I, which increases gradually in diameter until it finally terminates in the usual bell I'. On pipe I may be arranged the 35 valve J, for letting out the water.

On the valves D, E, and F operate the usual pistons, provided on their pistons' stems with the usual finger-pieces K, L, and N, which the operator presses when it is desired to change 40 the tone.

On the valve D is arranged the branch pipe O, through which passes the wind when the finger-piece K is depressed. A similar branch

pipe P is arranged on the valve E, and a like 45 one Q is held on the valve F. When the operator blows into the mouth-piece B and the pistons in the valves D, E, and F are in the normal position, the wind travels from the mouth-piece B into the pipe C to the valve D, and from the latter by the short branch pipe G 50 into the valve E, and from the latter through the short branch pipe H into the valve F, and from the latter into the end pipe I. When either of the pistons in the valves D, E, and F are pressed, the wind travels, in addition to 55 the route above described, through the branch pipes O, P, and Q, respectively, according to the piston operated on.

In cornets as heretofore constructed the end pipe I commenced in the first valve D, and 60 consequently was very short, so that the wind when traveling through the same produced a thin, cheap, and unmusical tone. By the arrangement shown and described the end pipe I is increased in length considerably, so that 65 the bell part of the end pipe is made considerably larger without throwing the instrument out of tune. It is understood that the gradual increase of the end pipe I must be in harmony with the length, as otherwise no musical 70 sound could be produced.

Having thus described my invention, what I claim as new, and desire to secure by Letters Patent, is—

A Pyrenet piston-valve cornet comprising 75 the valves connected with each other, a mouth-piece pipe of uniform diameter and leading to the first one of the said valves, and an end pipe having a bell and leading from the third 80 of the said valves and gradually increasing in size from the said third valve, substantially as described.

JOHN F. STRATTON.
